UNITED STATES PATENT OFFICE

JOHN O. SIMPSON, OF BRISTOL, CONNECTICUT, ASSIGNOR TO THE E. INGRAHAM COMPANY, OF BRISTOL, CONNECTICUT, A CORPORATION

WATCHCASE

Application filed July 27, 1932. Serial No. 624,938.

This invention relates to watchcases, and particularly to cases for wrist-strap watches of the type in which there are provided at laterally opposite portions offstanding ears 5 which furnish a means whereby the sections of the strap may be connected with the casing. These ears are ordinarily pierced to provide bearings for the pintles of strap-connecting members.

10 Such cases are usually formed of a front case member and a back case member, each of which is provided with an offstanding flange, and these flanges are preferably so proportioned that the flange of the back case member will telescope within the flange of the front case member to thus enclose the watch movement; complementary interengaging means being provided on the flanges of the two members for maintaining them in 15 assembled relation.

20 Due to the arrangement of the case members with the flange of the front case member located exteriorly of the flange of the back case member, the ears, above referred to, are ordinarily provided upon the flange of the front case member, and it is to the formation of this front case member, therefore, that the present invention is primarily directed, and in connection with which it will 25 be described.

20 Due to the relatively small size of the cases of wrist-strap watches and the fact that they are formed by die-stamping operations, usually from sheet metal, it has heretofore 35 been found necessary, in forming the ears referred to by means of complementary dies, to so design and arrange the side walls of the ears that the members of the male die by which they are formed may extend between 40 these side walls and to thereafter fill in the space thus formed between the side walls with solder or other metal or material to guard against distortion and collapsing of the ears and to fill in and appropriately finish 45 the ears and to provide therein bearings of adequate strength and extend for the pintles of the strap-connecting members.

Obviously, ears thus formed are rigid, and the strap-connecting means used in conjunction therewith ordinarily comprises a cylin-

der around which the strap bears, this cylinder being of a length to span the space between the opposed inner faces of the ears and being connected with the ears by a rod passing through it and through the bearings 55 formed by the piercing of the ears and headed over or riveted at its ends against the exterior faces of the ears to prevent its disengagement.

It will be apparent that the operations of 60 filling in the spaces between the side walls of the ears with solder or the like, and the assembling of the strap portions with the ears by connecting means comprising the parts mentioned, entail a quite appreciable 65 manufacturing cost which, when considered in connection with the production of wrist watches to sell at low retail prices, is out of all proportion to the sales value of the cases 70 thereof.

Moreover, where a filling of solder or other material different from that of which the case member is formed is used between the walls of the ears, the case member cannot be plated with the desired uniformity due to 75 this difference in material.

One object of the present invention is to provide a watchcase having all of the essential features of construction and appearance 80 present in watchcases of the type manufactured as above explained but in which the ears are so formed as to materially reduce the cost of manufacture.

Another object, which is accomplished by virtue of the novel formation of the ears, is 85 to provide connecting means for the strap portions which do not entail the expensive assembling operation employed as described, and which will take plating uniformly.

In accomplishing these objects, the strap- 90 attaching ears are formed without the necessity for the use of solder or other filling material, and they are of a sufficiently resilient or deformable nature to admit of the use with them of a strap-connecting member 95 made of a single piece and capable of being assembled between the ears with the strap applied to it by the simple expedient of spreading the ears to admit the pintles of the connecting member to its pierced bearings 100.

and then returning the ears to normal position to lock the connecting member and the strap carried thereby in place.

With these objects in view, the invention 5 contemplates a sheet material case member for wrist-strap watches, having a flange of the usual type, this flange provided with off-standing ears furnishing a means for attachment of a strap to the case, the ears being 10 formed integral with the flange and each comprising two thicknesses of the material of the flange arranged in intimate contact and pierced to provide bearings for a strap-connecting member of novel form, all as will 15 be explained hereinafter more fully and finally claimed.

In the accompanying drawing illustrating the invention, in the several figures of which like parts are similarly designated,

20 Fig. 1 is an interior plan view of a front case member of a wrist-strap watch of the "baguette" type embodying the invention;

Fig. 2 is an end elevation thereof;

Fig. 3 is a side elevation thereof;

25 Fig. 4 is an enlarged end elevation with the ears and strap-connecting member in section along the line 4—4 of Fig. 1;

Fig. 5 is a fragmentary section taken on the line 5—5 of Fig. 4, and on the scale of 30 Fig. 4, and showing a portion of a strap connected with the case;

Fig. 6 is an inside plan view of a case member partially shaped in accordance with the practice of the invention and

35 Fig. 7 is an end elevation thereof;

Fig. 8 is a perspective view looking at the inside of the finished case member; and

Fig. 9 is a perspective view of the strap-connecting member.

40 In forming a case member in accordance with the practice of the invention, a blank *a* is appropriately shaped up to the form shown in Figs. 6 and 7, portions *b* thereof being provided in the blank from which the ears 45 are formed. After the blank has been given the shape illustrated in Figs. 6 and 7, it is completed by straightening up the flange, closing together the two thicknesses of the ear-forming portions in intimate contact, cutting out the dial opening *c*, piercing the ears, and thereafter plating, polishing and otherwise appropriately treating it to produce the finished article having, in general, the appearance illustrated in Fig. 8.

55 Referring now to Figs. 1 to 5 inclusive, it will be seen that the finished front case member thus produced comprises a bezel 1 delimiting the dial opening *c* and a continuous, unbroken, integral flange 2 provided at lat- 60 erally opposite portions with pairs of ears 3—3 of such configuration as to produce an attractive design free of objectionable angular contours, as illustrated particularly in Fig. 3. As indicated, each of the ears 3 is formed integral with the flange 2 and com-

prises two connected thicknesses of the material thereof in intimate contact.

The ears thus formed compare favorably in strength, appearance and functional efficiency with those formed in accordance with the now prevalent practice hereinabove referred to. However, they may be formed as described with such an appreciable saving in material and labor as to greatly enhance manufacturing expediency in the production of 75 the case members.

Furthermore, as there is no combination of different materials in the ears, they may be provided with a uniform, equally-tenaciously-adhering plating over all of their exposed 80 surfaces.

Moreover, when the ears are pierced as indicated at 4 to provide aligned bearing openings for the strap-connecting means, the bearings provided by such openings are of 85 sufficient axial extent to impart the requisite strength to the strap connection.

The strap-connecting member comprises, preferably, a solid bar 5 having its ends reduced to provide pintles 6 and stop shoulders 90 7 and, when this bar is passed through the loop provided for it in the strap, it and the strap with it may be connected to the case member by the simple expedient of spreading the ears 3 relatively to each other sufficiently to permit the pintles 6 to enter the bearing openings 4, and thereafter returning the ears to their normal relationship as shown.

Obviously, by providing connecting means 100 for the straps in the simple form of solid bars, with pintles integral therewith, and assembling them, with the straps applied to them, by the simple operations referred to, the assembling of the strap on the case is 105 greatly simplified in comparison with this operation as now generally practiced.

Thus, in accordance with the invention, watchcases which are in all material respects the equivalent of those as now commonly constructed, and which in some respects are superior thereto, may be produced at a considerable saving in material and labor without sacrificing anything of symmetry of design, 110 strength and utility.

115 Various changes and modifications are considered to be within the spirit of the invention and the scope of the following claims.

I claim:

120 1. A sheet-metal case-member for wrist-strap watches having a bezel and a flange integral therewith provided with offstanding ears furnishing a means for attachment of a strap, each of said ears formed integral with said flange and comprising two thicknesses 125 of the sheet-metal of said flange folded together along a convexly-curved line forming the upper edge of the ear.

130 2. A sheet-metal case-member for wrist-strap watches having a bezel provided with

a convexly curved upper surface, and a flange integral therewith provided with offstanding ears furnishing a means of attachment of a strap, each of said ears formed integral with 5 said flange and comprising two thicknesses of the sheet-metal of said flange folded together along a convexly curved line forming the upper edge of the ear, the convexly curved upper edge of each ear blending with the 10 convexly curved upper surface of the bezel.

3. A sheet-metal case-member for wrist-strap watches having a bezel and a flange integral therewith provided with offstanding ears furnishing a means of attachment of a 15 strap, each of said ears formed integral with said flange and comprising two thicknesses of the sheet-metal of said flange folded together along a convexly curved line forming the upper edge of the ear, the thickness of each 20 ear being substantially just twice the thickness of the original sheet-metal.

4. A sheet-metal case-member for wrist-strap watches having a bezel and a flange integral therewith provided with offstand- 25 ing ears furnishing a means of attachment of a strap, each of said ears formed integral with said flange and comprising two thick- 30 ness of the sheet-metal of said flange folded together along a convexly curved line forming the upper edge of the ear, the thick- 35 ness of each ear being substantially just twice the thickness of the original sheet- metal, and the distance of extension out- 40 ward of each ear being greatly less its height.

5. A sheet-metal case-member for wrist-strap watches having a bezel provided with a convexly curved upper surface, and a flange integral therewith provided with offstanding ears furnishing a means of attachment of a 45 strap, each of said ears formed integral with said flange and comprising two thicknesses of the sheet-metal of said flange folded together along a convexly curved line forming the upper edge of the ear, the thickness of 50 each ear being substantially just twice the thickness of the original sheet-metal and the distance of extension outward of each ear being greatly less than its height, and the convexly curved upper edge of each ear blending with the convexly curved upper surface of the bezel.

6. A sheet-metal case-member for wrist-strap watches having a bezel and a flange integral therewith provided with offstanding 55 ears furnishing a means of attachment of a strap, each of said ears formed integral with said flange and comprising two thicknesses of the sheet-metal folded together, the thick- 60 ness of each ear being substantially just twice the thickness of the original sheet-metal, and the distance of extension outward of each ear being greatly less than its height.

In testimony whereof, I have signed this specification.

JOHN O. SIMPSON.
